UNITED STATES PATENT OFFICE.

CHARLES HERMAN FREEBURG, OF ERIE, PENNSYLVANIA.

DRINKING-CUP.

1,151,869.

Specification of Letters Patent. Patented Aug. 31, 1915.

Application filed January 8, 1915. Serial No. 1,115.

To all whom it may concern:

Be it known that I, CHARLES H. FREEBURG, a citizen of the United States, and a resident of Erie, in the county of Erie and State of Pennsylvania, have invented certain new and useful Improvements in Drinking-Cups, of which the following is a specification.

My invention relates to drinking cups, of a pocket or collapsible type, and one of the main objects thereof is to provide a permanent, sanitary, compact, and comparatively inexpensive cup which may be carried on the person for use at any time, and particularly in such States or localities where common drinking cups have been prohibited by law; a further object is to provide means in such cups for ease of drinking the contents thereof without the necessity for tilting the same, thereby overcoming the frequent spilling of liquids over a person on a railway train; a further object is to so form the drinking means as to serve as a strengthener for the cup; a further object is to form the cup as to permit the removal of said drinking means; and a further object is to so form the cup as to protect the mouthpiece or mouthpieces against contact with exterior objects when said cup is not in use.

My invention is fully described in the following specification, of which the accompanying drawings form a part, in which like reference characters are used to designate like parts in each of the views, and in which:

Figure 1 is a perspective view of a cup constructed in accordance with my present invention, collapsed; Fig. 2 is a central, vertical, longitudinal, section therethrough, when in use; and Fig. 3 is a section taken on the line 3—3 of Fig. 2.

In the drawings forming a part of this application I have shown a present preferred form of embodiment of my invention, comprising a bag-like cup 4 formed of side plates 5 and 6 of flexible material joined at their edges at 7 and 8, and bottom 9, the entire cup being preferably formed of one piece of material, such as celluloid, alone or fabric reinforced, rubber, fiber, or suitable equivalent, and I provide a notch 10 at the top of each cup edge. These side plates are preferably formed with upwardly and outwardly inclined edges, and the upper edges formed on the arc of a circle whereby, when the cup is spread open, the top edge thereof is in one plane, and I may also, as shown,

provide small inwardly directed protuberances or knobs 11 in each plate, adjacent the lower corners thereof, one knob on each plate registering with a corresponding knob on the other plate to hold a U-shaped tube 12 in the bottom of said cup.

The tube 12 has an opening 13 in the bottom of the cup to permit the liquid contents to pass to the mouthpieces 14 when suction is applied to one or the other by a person and thus into his mouth, thereby avoiding the necessity for tilting the cup, although said cup may be tilted and drunk from in the ordinary manner if desired; to maintain the two vertical tube sections in relative positions I employ a brace rod either secured thereto, or connected therewith in any manner, said tube and brace being preferably, although not necessarily, composed of non-corrosive metal, hard rubber, glass, or other suitable material, but it may also be composed of the material of the cup, if desired.

The side plates being made of flat material, the tendency thereof is to remain in close parallelism with each other, and the inclined edges are thereby maintained at a distance from the upper ends of the tube 12, thus inclosing and protecting the mouthpieces 14. When the cup is to be used, the upper edges thereof are manually forced into contact with the respective tube sections, this distending the cup transversely and also causing the mouthpieces 14 to project from the cup through the respective notches 10, and the cup is in position for use. When this manual pressure is released, the cup resumes the position shown in Fig. 1, flat, and ready for storage in a pocket, handbag, or the like.

While I have shown one design of the cup, I do not limit myself thereto, nor to the material of the cup or tube, as changes may be made thereover, within the scope of the following claims, and within the spirit of the invention.

Having fully described my invention, what I claim as new, and desire to secure by Letters Patent, is:

1. A cup, composed of flat side plates of flexible material joined at their bottoms and side edges, a U-shaped tube therein having an opening in the bottom of said cup and open mouthpieces, and means for holding said tube in said cup, said side plates being normally in parallelism and covering said mouthpieces, but said mouthpieces being

projected from said cup when said edges are manually forced toward each other.

2. A cup, composed of flat side plates of flexible material joined at their bottoms and 5 side edges, a U-shaped tube therein having an opening in the bottom of said cup and open, outwardly directed, mouthpieces, said side plates being normally in parallelism and covering said mouthpieces and having,

each, inwardly directed, registering, knobs 10 for holding said tube in position.

In testimony whereof I have signed my name to this specification in the presence of two subscribing witnesses.

CHARLES HERMAN FREEBURG.
